UNITED STATES PATENT OFFICE.

JAMES B. DODDS, OF DENVER, COLORADO.

CONCENTRATOR.

Application filed December 29, 1925. Serial No. 78,183.

My invention relates to concentrators, and its principal object is to provide a machine of simple construction particularly adapted for the separation of values from sands and other gangue without the employment of water or other liquid.

A further object of the invention is to provide in the machine of the above described character means for the separation of the values in material under treatment by upwardly directed impulses, distributed over the entire extent thereof; another object is to expedite and promote the separative action by laterally reciprocating movement of a table on which the material is treated, and still another object resides in the provision of means whereby a partial discharge of the separated metals is effected at a plurality of different points in the movement of the material along the table.

Further advantages of the invention will be found in details of construction and a novel arrangement of parts as fully set forth in the following description with reference to the accompanying drawings.

In the drawings, in the several views of which like parts are similarly designated,

Figure 1 represents a side elevation of the concentrating machine, the upper portion 30 of its supporting frame including the feed-hopper, having been omitted,

Figure 2, a transverse vertical section taken on the line 2-2 Figure 1,

Figure 3, a front elevation of the machine, including the feed-hopper, looking in the direction of the arrow A in Figure 1.

Figure 4, a plan view of the table of the machine,

Figure 5, an enlarged plan view of a portion of the table drawn to a larger scale, showing one of the appliances provided to effect a partial separation and discharge during the movement of the material along the table,

Figure 6, an enlarged section taken on the line 6-6, Figure 5, looking in the direction of the arrow B,

Figure 7, a similar section in the same plane looking in the opposite direction, and

Figure 8, represents a fragmentary sectional elevation showing a modified method of subjecting the deck of the concentrating table to upwardly directed impulses by fluid pressure.

Referring in detail to the drawings, the

concentrating machine comprises a supporting structure composed of three inter-connected upright frame-members 5, 6 and 7. A superstructure 8 of the frames 5 and 6 supports a hopper 9 into which the material under treatment is fed from a conveniently located source of supply, and an endless belt 10 beneath the hopper carries the material to a point of discharge above the upper end portion of an inclined table 12 65 which in the operation of the machine concentrates the material for the separation of its minerals from the sands and gangue in which they are contained.

The feed-belt 10 is supported on two rollers 13, mounted for rotation in boxes 14 on horizontal sills 15 secured between the frames 5 and 6 of the supporting structure, and the boxes of one of the rollers are slidably mounted to adjust the tension of the belt through the medium of screw-bolts 16.

The concentrating table mentioned hereinbefore, is suspended in a lengthwise inclined position by means of four rods 17 which are pivotally connected with ears 18 80 on the sides of the table to permit of its lateral reciprocation.

The rods pass loosely through openings in cross-pieces at the upper ends of the frames 6 and 7, and their upper ends are 85 screw-threaded for the application of wing-nuts 19 by means of which they are supported on the frames.

The nuts provide a convenient medium for the adjustment of the rods in order 90 to vary the inclination of the table in accordance with the nature of the material under treatment.

The table 12 comprises a rifled deck 20 composed of canvas or other flexible material peripherally fastened in a rectangular frame 21 and loosely supported on cross-slats 22. Hinged at the lower end of the deck-frame is the movable member 23 of a bellows, the air-chamber 24 of which is defined by sides 25 of thin leather or the like, the member 23 being provided with a valve-controlled inlet 26 for the admission of air during downward movement thereof.

The table is furthermore provided with two side-rails 27 and 28 extending above its deck, and with appliances for the partial separation and discharge of the minerals moving along the rifles of the deck.

The rifles 29 extend obliquely to the lon-

gitudinal axis of the table with their lower ends terminating at a distance from the respective side-rail 27. The upper edges of the riffles slant inwardly as shown in Figure 6, and the side-rail 27 has in alinement with said edges of the riffles, outlet-openings 30, preferably provided with outwardly projecting tubular spouts 31.

The separating appliances above referred

- 10 to, which in the operation of the machine, effect a partial discharge of the values through the openings 30, consist of metal plates of angular, substantially V-shaped form, one member 32 of which occupies the spaces between the riffles and the apertured side of the table in alinement with the riffles and the other member 33 of which extends toward the next lower riffles and terminates at a distance from the upper edge thereof.
- 15 29 The plates are fastened upon the deck of the table by screws 34 and the inwardly extending members 33 of the same are provided with upstanding flanges 35 which extend to and below the discharge-openings in the side of the table.
- 25 30 35 The uppermost riffle of the oblique series is disposed at a distance below the upper edge of the deck to provide a space 134 upon which the feed discharged from the apron 10 is received, and a guide-strip 35 extending from the side of the table obliquely to the upper one of the riffles 29, directs the feed toward the uppermost portion of the same.

A driving shaft 36 mounted in boxes on the frame 6 beneath the upper end of the inclined table, carries a pulley 37 for its connection with a conveniently located motor.

Two eccentrics 38 on the same shaft, have their rods 39 in pivotal connection with the movable member 23 of the bellows at the upper end thereof, to impart a reciprocating motion to the member by rotation of the shaft, and a sprocket wheel 40 on the shaft, together with corresponding wheels 42 and 41, one of the rollers 13 of the feed apron and an intermediate shaft 43, operate the apron through the medium of chains 44 and 45.

50 A lateral vibrating motion is imparted to the table by means of a cam 46 mounted on a shaft 47 supported in boxes on the frames 6 and 7, in cooperation with springs 55 engaging the opposite sides of the table. The tension of the springs may be varied by adjustment of screws 56. A chain 48 connects the cam shaft with a lower parallel shaft 49, and the latter is by means of beveled gear wheels 50 and 51 connected with the driving shaft.

60 In the operation of the machine, the material fed onto the upper portion of the table is by means of the guide-strip 35 directed to the upper portion of the upper one of the series of oblique riffles 29.

65 The laterally shaking motion of the table,

imparted thereto by the cam 46 causes the material to move downwardly across the riffles while the minerals contained in the material will form a stratum below the lighter gangue and be caught by the slanting upper edges of the riffles.

The separation of the mineral from its containing rock or sand is greatly expedited and promoted by the impulses to which the flexible deck is subjected by the intermittent compression of air in the bellows.

The values moving downwardly along the riffles continue their movement along the therewith alined edges of the members 32 of the separating plates which are of lesser depth, with the result that the heavier and most valuable particles pass through the openings 30 in the side 27 of the table, while the minerals of lesser value and the gangue with which they are still intermixed, pass across the member 32 and are by the flanged member 33 of the separator, directed toward the next following riffle.

The operation hereinabove described is repeated until the material reaches the lower end of the table where the remaining minerals are discharged at the lower edge of the lowermost riffle while the gangue passes across the riffle and thence over the edge of the table.

By the operation of my machine, a practically clean separation of the minerals from the sands, rock and other gangue with which they are associated may be obtained in a simple manner and without the use of water or other liquids necessary in wet concentration.

The operation may if so desired, be aided by tilting the table slightly toward its discharge side, and the upwardly directed impulses by fluid pressure may be produced by means other than the bellows, as for example, an intermittently-opened valve in connection with a source of compressed air. An arrangement of this kind has been illustrated in Figure 8 in which 57 designates the air chamber beneath the deck of the table, 58 a valve adapted to connect the chamber alternately with a pipe 59 connected with a source of compressed air and with the atmosphere, and an eccentric 60 by which the valve is operated. Other variations in the construction and arrangement of the parts of the machine may be resorted to without departing from the scope or spirit of the invention.

What I claim and desire to secure by Letters Patent is:

1. In a concentrator, a table having an impervious rifled flexible deck, and means for subjecting the deck to upwardly directed impulses by a fluid medium underneath the deck.
2. In a concentrator, a table having an impervious rifled flexible deck, a bellows be-

low the deck adapted to subject the same to upwardly directed impulses by intermittent air-compression, and means for the operation of the bellows.

5 3. In a concentrator, a moving table having a deck and a side-rail along an edge thereof, provided with a discharge-opening, a riffle on the deck, slanting toward the side-rail in line with the discharge-opening, and 10 a member between the riffle and the opening to direct part of matter caught behind the riffle to the opening, the member being lower than the riffle for the movement of the other part of said matter across the member.

15 4. In a concentrator, a moving table having a deck and a side-rail along an edge thereof, provided with a discharge-opening, a riffle on the deck, slanting toward the side-rail in line with the discharge-opening, and 20 an appliance between the riffle and the opening for the partial separation and discharge of matter caught behind the riffle, comprising a member of lesser height than the riffle forming an extension of the same to the 25 opening, and a member extending obliquely inwardly from the opening for the direction of matter moving across the first mentioned member.

5 5. In a concentrator, a moving table having a deck and a side-rail along an edge thereof, provided with a discharge-opening, a riffle on the deck, slanting toward the side-rail in line with the discharge-opening, and 30 an appliance between the riffle and the opening for the partial separation and discharge of matter caught behind the riffle, comprising a member of lesser height than the riffle forming an extension of the same to the 35 opening, and a flanged member extending 40 obliquely inwardly from the opening for the

direction of matter moving across the first mentioned member.

6. In a concentrator, a moving table having a deck and a side-rail along an edge thereof, provided with a plurality of discharge-openings, riffles on the deck slanting toward the discharge-openings, separating members of lesser height than the riffles, forming extensions thereof to the openings, and guide-members extending obliquely 45 from the openings toward the next following riffle, the lower riffles of the series terminating in the lower edge of the deck. 50

7. In a concentrator, a moving table having a deck and a side-rail along an edge thereof, provided with a plurality of discharge-openings, riffles on the deck slanting toward the discharge-openings, separating members of lesser height than the riffles, forming extensions thereof to the openings, 55 and guide members extending obliquely from the openings toward the next following riffles. 60

8. In a concentrator, a moving table having an impervious flexible deck and a side-rail along an edge thereof, having a plurality of discharge-openings, riffles on the deck slanting toward the discharge-openings, separating members of lesser height than the riffles, forming extensions thereof to the 65 70 openings, guide-members extending obliquely from the openings toward the next following riffles, the lower riffle of the series terminating in the lower edge of the deck, and means for subjecting the deck to upwardly directed impulses. 75

In testimony whereof, I have hereunto affixed my signature.

JAMES B. DODDS.
